[57] CLAIM

The ornamental design for a Christmas tree ornament display, as shown and described.

DESCRIPTION

FIG. 1 is a perspective view of a Christmas tree ornament display showing my new design;
FIG. 2 is a top plan view thereof;
FIG. 3 is a front elevational view thereof;
FIG. 4 is a rear elevational view thereof;
FIG. 5 is a bottom plan view thereof;
FIG. 6 is a right side elevational view thereof; and,
FIG. 7 is a left side elevational view thereof.

The star in FIG. 1, and the cords in FIGS. 2, 4, 6 and 7, are shown in broken lines for illustrative purposes only and form no part of the claimed design.
